DESIGN FOR A COMBINED BOTTLE AND CLOSURE CAP

Frank McIntosh, New York, N. Y., assignor to Letheric Incorporated, New York, N. Y., a corporation of New York

Application March 16, 1938, Serial No. 75,867

Term of patent 7 years

To all whom it may concern:

Be it known that I, Frank McIntosh, a citizen of the United States, residing at New York city, in the county of New York and State of New York, have invented a new, original, and ornamental
Design for a Combined Bottle and Closure Cap, of which the following is a specification, reference being had to the accompanying drawing, forming part thereof.

In the drawing:

Fig. 1 is a top view of a combined bottle and closure cap embodying my new design;

Fig. 2 is a front view thereof; and
Fig. 3 is a side view thereof.

The design is characterized by a combined bottle and closure cap, each of the specific form shown, associated essentially in the manner illustrated.

I claim:

The ornamental design for a combined bottle and closure cap, substantially as shown and described.

FRANK MCINTOSH.
